UNITED STATES PATENT OFFICE.

RICHARD SAVAGE, OF SAN FRANCISCO, CALIFORNIA.

MOLDING-MACHINE.

SPECIFICATION forming part of Letters Patent No. 349,815, dated September 28, 1886.

Application filed March 31, 1885. Serial No. 160,836. (No model.)

To all whom it may concern:

Be it known that I, RICHARD SAVAGE, of the city and county of San Francisco, State of California, have invented an Improvement in 5 Molding and Core-Making Machines; and I hereby declare the following to be a full, clear, and exact description of the same.

My invention relates to an apparatus for the making of molds for castings.

10 It consists of a directing-chute, having front and rear walls and side walls, a' , into which the sand is received from a hopper above; a joint or joints at some portion of the length of the chute, so that it may be deflected to direct 15 the sand into different parts of the flask beneath; a series of two or more chutes, formed by placing chutes side by side, or by placing vertical partitions in one long chute, so that different flasks may be filled beneath the different sections; a means for supplying sand to 20 the hopper, and regulating-gates by which the supply may be cut off from any one or more of the sections, as will be more fully explained by reference to the accompanying drawings, in 25 which—

Figure 1 is a front view of the apparatus. Fig. 2 is a vertical transverse section taken through XX, Fig. 1. Fig. 3 is a plan view of the rollers and clutch mechanism enlarged. 30 Fig. 4 is a view of the flask and cross-bars.

A is a chute having front and rear walls and side walls, a' , which is placed nearly or quite vertical, and is of sufficient height, so that sand falling through it will attain momentum enough to impact itself and become solid in the flask where it falls. The lower sections, B, of the chute are fitted in sockets, 35 as shown at C, so that they may be turned to a small angle with the main portion of the 40 chute, thus directing the sand to one side or the other of a vertical plane without too greatly impeding its momentum. The advantage of this construction—that is, having a chute inclosed on all sides—lies, first, in the 45 fact that it keeps the sand in a more compact body, and prevents it being scattered by the resistance of the air, which would occur if it were caused to slide down the inclined plane with

one side exposed, as under such conditions the open air upon one side would offer a certain resistance, which objection is overcome in my chute. Another advantage is that it may be moved from one side to the other over the flask or mold below, and may incline to either side of the perpendicular, as the sand is guided by either side of the chute. 50 55

D is a flask, which is made in the usual manner, to contain the pattern of the article to be cast, and it is mounted upon a carriage or truck, E, so that it may be easily moved beneath the chute or withdrawn from it after the mold is finished. 60

In order to insure the sand being filled in solid in every portion of the flask, the cross-bars F are made of thin iron or other sheet 65 metal. These cross-bars are either perforated with holes, or they may be corrugated or have projections, so that the sand will unite through and around them, and thus become a solid mass after the flask is filled. By making these thin 70 plates with their edges presented to the falling body of sand they do not in any way impede it, and it falls so as to pack thoroughly without any necessity of tucking or pressing it down under the bars with the fingers, which must be 75 done when the ordinary wooden bars are used. This construction enables me to employ the chute and the force of gravitation to form the molds in the flask, which could not otherwise be done. By means of the jointed section it is 80 possible to direct the sand to any part of a flask of reasonable size without moving the whole chute, which would be a difficult operation on account of its height and bulk. If, however, the flask be too long or too wide for 85 this operation, it will be seen that the truck or carriage upon which it is mounted may be moved while the flask is being filled, so that all parts of the work can be completed. The upper end of the chute A is made hopper or 90 diverging shaped, and above it is fixed a receptacle or hopper, G, from which sand is delivered into the chute by means of a swinging gate, H, and a feed-roller, J, having teeth, flanges, or projections K, and which may be 95 provided with a series of cleaning-arms; this

operation being more fully described in another application for a patent which I have made bearing the same date as the present one.

The hopper G and chute A may have as great a length in a horizontal direction as may be desired, so that several flasks can be placed beneath it at one time; and in order to separate the work, so that the different flasks can be filled independently, I divide the chute and hopper into separate hoppers and chutes by vertical diaphragms or partitions. In practice it will be found convenient to arrange separate chutes slightly apart; but a continuous structure divided by partitions would be sufficient to make a series of chutes.

The swinging gate H, which regulates the discharge of the sand, has a weighted lever or arm, I, attached to its front, which tends to keep it closed when not in use. When it is desired to open the gate H, it is done by means of a cord, i, attached to the gate, passing thence around direction-pulleys, and being connected with one end of a lever, L, so that when this lever L is moved or oscillated in one direction it will open the gate H, and when it is moved in the opposite direction it will release the cord i and allow the gate to close. The lever L is moved by cords L', which hang down in front of the apparatus to a point within reach of the workmen. This lever L also serves to set the feed-roller J in operation when the gate is open, or stop it when the gate is closed, in the following manner: The rollers J are made in lengths each equal to the length of the section of the chute over which it stands. These rollers are loosely mounted upon a shaft, J', which extends the entire length of the apparatus. Friction-clutches are fitted at each of the divisions M, so that any one or all of the feed-rollers may be set in motion or stopped at will. In the present case I have shown the ordinary conical friction-clutches, the portion n, which forms the hollow cone, being fixed inside the roller J. The driving-cone n' is fitted upon a feather, o', on the shaft J', so that it rotates with the shaft, and may be caused to slide in or out of contact with the hollow cone n, thus driving the feed-roller or allowing it to remain stationary. The sliding cone n' is operated by a clutch-lever, P, which is bent at right-angles and pivoted or journaled to a fixed beam with an extension, r, which forms a nut fitting upon a screw, r'. The lever L, before described, is fixed upon one end of this screw, as shown in Fig. 3, and when one end of the lever is pulled down by its cord L' the screw will operate to move the part r and arm p in one direction, so as to disengage the clutch, and when pulled in the other direction the screw will move the arm so as to cause the clutch to engage.

In order to supply the receiver or hopper G with sand above those parts of the chute only which are being used, it is necessary to employ valves or gates T, which are operated

by arms or levers T', Figs. 1 and 2. These valves serve to open and close passages P in the bottom of a horizontal trough, O, into which the sand is delivered by an elevator, N. The sand is carried along the trough O by means of a horizontal traveling belt, S, having scrapers or projections Q fixed to it, and by these projections the sand, which is delivered into the trough by the elevator N, is distributed from one end to the other of the trough. It will be seen that when either section of the chute A is to be used it will only be necessary to open the gate H, throw the clutch n' into gear, so as to operate the feed-rollers J, and at the same time move the valve or gate T, corresponding with the section, so as to open the discharge-passages P of the trough O, when the sand will be delivered to that portion of the apparatus. Each section of the apparatus is provided with a similar mechanism, and they are therefore independent of each other. Any sand which may fall out of the flasks E will be caught upon a horizontal traveling belt, V, below the flasks and carriages, and will be carried upon it and delivered into the receiver W. From this receiver the elevator N takes its supply and delivers it into the horizontal trough O, as before described. It will be manifest that various modifications of the mechanism for operating or stopping the different sections of the chute may be made, which will readily suggest themselves to any one skilled in the art, but I have here shown a mechanism which is very satisfactory in practice.

Having thus described my invention, what I claim as new, and desire to secure by Letters Patent, is—

1. A molding or core-making apparatus consisting of a hopper and a discharge-chute inclosed on all sides, the said chute extending downward from the hopper-bottom in an approximately-vertical direction, whereby the sand is discharged into the molds or upon the core by gravitation, substantially as described.

2. A molding apparatus consisting of one or more vertical and jointed chutes through which sand is delivered from a hopper or receiver above for making molds, in combination with a horizontal trough situated above the receiver, having a perforated bottom and controlling-gates, and a horizontally-moving belt, with lugs or projections moving along said trough, substantially as herein described.

3. A molding apparatus consisting of a jointed chute, with a sand-feed mechanism and sand-receiver, in combination with two or more chutes, and a horizontal supply-trough with a perforated bottom and gates, whereby two or more independent sections may be opened and closed, substantially as herein described.

4. A molding apparatus consisting of two or more independent chutes, and a supply

hopper or receptacle at the top, in combination with feed-rollers mounted loosely upon a driving-shaft, and clutch mechanisms by which the rollers may be engaged or disengaged, substantially as herein described.

5. A molding apparatus consisting of two or more independent chutes, and a supply hopper or receptacle at the top, in combination with feed-rollers and a hinged swinging

gate, and a mechanism whereby the gate may be opened and the rollers set in motion simultaneously, substantially as herein described.

In witness whereof I have hereunto set my hand.

RICHARD SAVAGE.
